US00D379133S

United States Patent [19]

Ahern, Jr. et al.

[11] Patent Number: Des. 379,133

[45] Date of Patent: **May 13, 1997

[54] FOOD STORAGE CONTAINER LID

[75] Inventors: **Richard B. Ahern, Jr.**, Akron; **Derek Campbell**, Dayton; **Maaike Evers**, Columbus, all of Ohio; **Debra A. Fritsch**, Grand Rapids, Mich.; **Norio Fujikawa**, Columbus, Ohio; **David Gresham**, East Hampton, N.Y.; **Paul J. Kudirka**, Ada; **Mark Metzler**, Alto, both of Mich.; **Donald J. Staufenberg**, Dublin, Ohio; **Michael Sullivan**, Ada, Mich.

[73] Assignees: **Rubbermaid Incorporated**, Wooster, Ohio; **Amway Corporation**, Ada, Mich.

[**] Term: 14 Years

[21] Appl. No.: 47,669

[22] Filed: Dec. 11, 1995

[51] LOC (6) Cl. 07-01

[52] U.S. Cl. D7/392.1; D7/391

[58] Field of Search D7/391, 392.1, D7/612, 538, 540, 542, 354, 392, 602, 629; D9/446, 523, 435, 454, 452; 220/356, 306; 215/320

[57] CLAIM

The ornamental design for a food storage container lid, as shown and described.

DESCRIPTION

FIG. 1 is a top right front perspective view of a food storage container lid showing our new design;
 FIG. 2 is a top plan view thereof;
 FIG. 3 is a bottom plan view thereof;
 FIG. 4 is a front elevational view thereof; the rear elevational view being a mirror image;
 FIG. 5 is a left side elevational view thereof; and,
 FIG. 6 is a right side elevational view thereof.
